(57) **CLAIM**

The ornamental design for a portable basketball backboard and rim assembly, as shown and described.

DESCRIPTION

FIG. 1 is a front view of a portable basketball backboard and rim assembly showing my new design;

FIG. 2 is a front left side slightly downward-looking perspective view thereof;

FIG. 3 is a front right side slightly downward-looking perspective view thereof;

FIG. 4 is a front left side slightly upward-looking perspective view thereof;

FIG. 5 is a front right side slightly upward-looking perspective view thereof;

FIG. 6 is a rear view thereof;

FIG. 7 is a side view, wherein the opposite side view is a mirror image thereof; and,

FIG. 8 is a front right side slightly upward-looking perspective view of an enlarged portion of the portable basketball backboard and rim assembly, shown separately for ease of illustration.

The broken lines depict portions of the portable basketball backboard and assembly that form no part of the claimed design.

1 Claim, 4 Drawing Sheets
